UNITED STATES PATENT OFFICE

MORRIS M. MARCUS, OF PHILADELPHIA, PENNSYLVANIA

SEPARABLE LAMP STAND

Application filed January 20, 1930. Serial No. 421,948.

This invention relates to the manufacture of electric floor or table lamps, and more particularly to improvements in the construction and general arrangement of the base or stand therefor.

Practically all electric lamps of the floor or table type and with which this invention is primarily concerned are provided with a vertically extending standard or pedestal and a base upon which said standard or pedestal is supported. Ordinarily this base is of relatively great transverse dimension with respect to that of the pedestal or standard whose length varies in accordance with the style of lamp. This construction, involving a wide and often bulky base and a slender and more or less long standard or pedestal, makes the shipment and storage of the lamps a particularly difficult and expensive problem.

Heretofore and prior to this invention, various attempts have been made from time to time to overcome the difficulties involved in shipping and storing lamp stands the bases and pedestals of which were shipped and stored in assembled relation. In some cases the lamp standard has been constructed of separable parts necessitating the use of separable electric connectors where each part was wired at the place of manufacture or necessitating wiring of the lamp after it had been assembled by the ultimate consignee thereof. Obviously, the employment of auxiliary electrical connectors within the lamp standard to effect the necessary electrical connection between the wired separable parts thereof increased the manufacturing cost of the lamp. On the other hand, where the separable parts of the lamp standard were not initially wired and supplied with electrical connectors special skill and care as well as time and labor were required on the part of the consignee to wire the lamp after he had assembled the several parts as received from the manufacturer.

Among the objects of the present invention is to provide a construction wherein the lamp standard or pedestal is separable from the base thereof and whereby all of the afore-

mentioned difficulties and objections may be obviated.

A further object of the invention is the provision of a lamp stand the base of which is separable from the pedestal or standard therefor whereby to reduce to a minimum the expense of shipping and storing these parts of the lamp stand.

A still further object of the invention is the provision in a lamp of a pedestal or standard therefor which is adapted for separable securement to the base of the lamp, the pedestal being further characterized in that it is adapted to be completely wired by the manufacturer thereof preliminarily to mounting the same upon its base.

Still another and more specific object of the invention is the provision of means for detachably securing together a lamp pedestal or standard and a base therefor, the latter member being provided with a central opening the vertical axis of which is substantially coincident with that of the pedestal or standard and of a diameter sufficient to permit the free passage therethrough of an electric plug with which the pedestal or standard is equipped at the place of manufacture thereof.

Further objects of the invention are to provide a rigid and secure connection between the separable lamp standard or pedestal and the supporting base therefor, to decrease the cost of manufacturing these parts, to increase the ease with which these parts may be assembled and to provide a lamp stand which approaches in external appearance those stands wherein the pedestal and base are formed integrally. Further objects and advantages of the invention will appear more fully hereinafter.

The invention consists substantially in the combination, construction, location and relative arrangement of parts, all as will appear more clearly from the detailed description to follow, as shown in the accompanying drawing and as finally pointed out in the appended claims.

In the accompanying drawing, which is for the purpose of illustrating certain preferred embodiments of the present invention:

Figure 1 is a vertical sectional view of a lamp stand constructed in accordance with the principles of the present invention;

Figure 2 is a view taken on the line 2—2 of Figure 1;

Figure 3 is a bottom plan view of the arrangement shown in Figure 1; and

Figure 4 is a bottom plan view of a modified arrangement embodying the principles of the present invention.

Referring now to the drawing and more particularly to Figures 1 to 3 thereof it will be observed that the lamp stand as constructed in accordance with this invention comprises a base 10 and a vertically extending pedestal or standard designated by the reference numeral 11. The base 10, it will be noted, is of a transverse dimension which is relatively great with respect to that of the pedestal or standard 11, the length of the latter varying in accordance with the particular style of lamp.

The base 10 is provided in the top surface thereof with a central aperture or opening 12 the vertical axis of which is substantially coincident with that of the standard or pedestal 11. Extending radially inwardly from the wall 13 of the opening 12 are a plurality of circumferentially spaced integrally formed lugs or bosses 14, the upper surfaces of which lie in a plane which parallels and is spaced downwardly from the horizontally extending plane of the top surface 17 of the base member 10. There is thus provided a depressed seat within the top of the base for supporting the lower end of the lamp pedestal or standard 11.

Arranged to be received within this depressed seat is a member 15 of generally tubular form, the lower end of which is flared to provide an outwardly and radially extending flange 16. This flange is adapted to rest upon the lugs or bosses 14 provided in the base 10 and is so designed that the upper surface of the flange 16 thereof lies substantially in the plane of the top surface 17 of the base 10. In other words, when the member 15 is supported upon the lugs or bosses 14 of the base in the manner shown in Figure 1 the top surface of the flange 16 is substantially flush with the surface 17 of the base 10.

The upper end of the tubular member 15 is interiorly threaded, as at 18, to threadedly receive the lower end of a vertically extending pipe 19. The upper end of this pipe 19 is adapted to support the usual electric lamp fixture (not shown). The pipe 19 is preferably enclosed within a brass tubing 20 in the manner and for the purpose well understood in the art.

Extending through the inner pipe 19 are the electric wires or conductors 21 the upper ends of which are suitably secured to the aforesaid electric lamp fixture and the lower ends of which are provided with a suitable

electric connector or plug 22. These electric wires 21 are threaded through the pipe 19 and the member 15 into which the pipe is threaded at the place of manufacture and preliminarily to assembling the standard 11 and the base 10. At the same time that the standard 11 is equipped with the electric wires 21 the latter are provided with the electrical connector 22. In order to permit the free passage of this electric connector 22 through the opening in the top of the base of the lamp, the inner ends of the radially extending lugs 14 are spaced apart a distance sufficient to permit the ready passage therebetween of the electric plug. In other words, the effective internal diameter of the opening provided in the base 10 is greater than the overall transverse dimension of the plug 22.

In assembling the lamp stand 11 and the base 10, this being effected by the retailer or ultimate user of the lamp, the member 15 is positioned with the flange 16 thereof resting within the depressed seat formed in the base. Suitable openings are provided in each of the lugs 14 of the base through which screws 23 are projected for threaded engagement with the base element 15 of the vertically extending standard or pedestal 11. In some instances the openings which are formed in the lugs or bosses 14 through which the screws 23 project are truly circular in form as indicated by the reference numeral 24 in Figure 3, whereas in other instances these openings may be in the form of open-ended slots, as indicated by the reference numeral 25 in Figure 3. Whether the openings 24 or the slots 25 are employed, they are preferably larger in size than the shank of the screws 23 so as to permit a certain degree of radial adjustment between the base member 15 of the pedestal and the base 10 and thereby effect proper centering of the former with respect to the latter.

In order to insure proper positionment of the member 15 relatively to its base 10 and to relieve the screws 23 of any strain due to relative rotation of the parts, the flange 16 of the member 15 may be provided with a downwardly extending flange 26, portions of which are cut out to provide a series of shoulders or abutments 27 respectively arranged to either side of each of the radially extending lugs or bosses 14.

Figure 4 illustrates a modified form of construction wherein the base 10 of the lamp is provided with a substantially continuous annular flange 28 in place of the plurality of radially extending lugs or bosses 14. This flange 28 defines a central opening 29 in the top of the base 10 and forms the bottom of a depressed seat for the base member 15 of the vertically extending standard or pedestal 11. Provided in this flange adjacent the inner peripheral edge thereof are a plurality of openings through which the securing screws 120

30 may be projected for threaded engagement with the base member 15, exactly as described in connection with the structure of Figure 1. These openings through which the screws 30 5 are projected may be in the form of radially extending slots such as are indicated by the reference numeral 31 of Figure 4 or arcuately formed elongated slots such as are indicated by the reference numeral 32. 10 In constructing the lamp, it will be understood that the pedestal or standard 11, including the pipe 19, the tubular member 20 and the base member 15, is constructed in its entirety and completely wired independently 15 of the base member 10 of the lamp. To assemble the lamp it is merely necessary to mount the base member 15 of the lamp pedestal within the seat provided therefor in the base 10 of the lamp, the parts 15 and 10 being 20 rigidly secured together by means of the screws 21, it being understood that the electric plug 22 is first threaded through the central opening or aperture of the base 10. Inasmuch as the screws 23 are inserted through 25 the bottom end of the lamp structure they are not visible when the lamp is viewed in its ordinary upright position and due to the fact that the member 15 more or less snugly fits within the seat provided therefor within the 30 base 10 the external aspect of the lamp is that of one wherein the base and vertically extending standard or pedestal are constructed integrally.

It will be understood of course that the invention is susceptible of various changes and modifications without departing from the real spirit or general principles of the invention and it is accordingly intended to claim the same broadly, as well as specifically, as 35 indicated in the appended claims.

What is claimed as new and useful is:—

1. In a lamp structure, in combination, a base, a pedestal adapted to project upwardly from said base and arranged for detachable securement thereto, electric wiring extending through the bore of said pedestal and emerging from the lower end thereof and provided at the extremity of the emerging portion thereof with an attachment plug 45 in such manner that said pedestal is wired complete and ready for use, said base being provided with an opening therein substantially coaxial with said pedestal and of sufficient diameter to permit the free passage therethrough of said plug, and a plurality of circumferentially spaced lugs projecting radially inwardly of said opening for supporting said pedestal upon said base.

2. In a lamp structure, in combination, a 50 base member, a depressed seat formed in the upper surface of said base member, said seat being provided with a central opening therein and with a plurality of slots spaced about said opening, a tubular pedestal member provided at the lower end thereof with an out-

wardly directed peripheral flange adapted to fit snugly within said seat such that the exposed upper surfaces of said base member and flange lie in a common plane, said pedestal member being equipped with electric wiring, including an attachment plug, whereby to render the same electrically complete prior to its securement to said base member, and means projecting through the slots in said base member and into engagement with said flange for maintaining said base member and pedestal in assembled relation, and means coacting with said slots to permit radial adjustment of said pedestal with respect to the base member and said opening being of sufficient size to permit the free passage therethrough of said plug preliminarily to securing said base and pedestal members together. 70 75 80

3. In a lamp structure, in combination, a support for a pedestal consisting of separable sections, one of said sections being in the form of a tubular sleeve the lower end of which is provided with an outwardly directed flange, the other of said sections being in the form of a plate having a depression therein of a configuration adapted to snugly receive said flange, the base of said depression being provided with a plurality of elongated slots, and means projecting upwardly through said slots for threaded engagement with said flange, said means being effective, when loosened, to permit lateral adjustment of one of said sections relatively to the other. 85 90 95

4. In a lamp structure, in combination, a vertically extending tubular standard, a base upon which said standard is adapted to be detachably supported, electric wiring in said standard and extending from the lower end thereof and terminating in an attachment plug, a seat in said base for receiving the lower end of the standard, said seat being provided with an opening of sufficient size to permit the passage therethrough of said attachment plug, a plurality of apertured lugs projecting radially inwardly of said opening, and means projecting through said lug apertures into threaded engagement with the lower end of said standard. 100 105 110

In testimony whereof, I have hereunto affixed my signature. 115

MORRIS M. MARCUS.
